United States Patent Office

Des. 185,625
Patented July 7, 1959

185,625

COMBINED CONTAINERS AND RACK THEREFOR

William Edward Cole, London, England, assignor to
Craxfords Limited, London, England

Application December 30, 1958, Serial No. 53,986

Claims priority, application Great Britain July 1, 1958

Term of patent 14 years

(Cl. D44—1)

FIG. 1.

FIG. 2.

FIG. 3.

FIG. 4.

FIG. 5.

Figure 1 is a fragmentary front perspective view from below of combined containers and rack therefor showing my new design;

Figure 2 is a fragmentary top plan;

Figure 3 is a fragmentary front elevation;

Figure 4 is a fragmentary rear elevation; and

Figure 5 is a fragmentary underneath plan, the article being of indefinite length, portions having been omitted from the intermediate section for ease of illustration.

The article is of indefinite length.

I claim:

The ornamental design for combined containers and rack therefor, as shown and described.
